CLAIM

The ornamental design for an optical display case, as shown and described.

DESCRIPTION

FIG. 1 is a top perspective view of an optical display case according to one arrangement of the present design;

FIG. 2 is a top plan view of the optical display case shown in FIG. 1;

FIG. 3 is a left side elevation view of the optical display case shown in FIG. 1, the right side elevation view being identical;

FIG. 4 is a bottom plan view of the optical display case shown in FIG. 1;

FIG. 5 is a back end elevation view of the optical display case shown in FIG. 1;

FIG. 6 is a front end elevation view of the optical display case shown in FIG. 1;

FIG. 7 is a top perspective view of an alternative arrangement of the optical display case according to the present design;

FIG. 8 is a top plan view of the optical display case shown in FIG. 7;

FIG. 9 is a left side elevation view of the optical display case shown in FIG. 7, the right side elevation view being identical;

FIG. 10 is a bottom plan view of the optical display case shown in FIG. 7; and,

FIG. 11 is an back end elevation view of the optical display case shown in FIG. 7, the front end elevation view being identical.

The phantom or broken lines shown herein are for illustrative purposes only and form no part of the claimed design.

It is certified that error appears in the above-identified patent and that said Letters Patent is hereby corrected as shown below:

Title page, illustration Figure, to be substituted with the Title page illustration figure (attached).

Delete Drawing Sheets 1-8 and substitute therefor Drawing sheets 1-4 (attached).

Title page.

DESCRIPTION, should read as follows:

-- Figure 1 is a top perspective view of an OPTICAL DISPLAY CASE according to the present design;

Figure 2 is a top view of the OPTICAL DISPLAY CASE shown in Figure 1;

Figure 3 is a left side elevation view of the OPTICAL DISPLAY CASE shown in Figure 1, the right side elevation view being identical;

Figure 4 is a bottom plan view of the OPTICAL DISPLAY CASE shown in Figure 1; and Figure 5 is a back end elevation view of the OPTICAL DISPLAY CASE shown in Figure 1, the front end elevation view being identical.

The phantom or broken lines shown herein are for illustrative purposes only and form no part of the claimed design. --.
